UNITED STATES PATENT OFFICE.

GEORGE C. FOOSE, OF DALTON, NEW YORK.

LAND-ROLLER.

SPECIFICATION forming part of Letters Patent No. 377,066, dated January 31, 1889.

Application filed June 11, 1887. Serial No. 240,970. (No model.)

To all whom it may concern:

Be it known that I, GEORGE C. FOOSE, a citizen of the United States, residing at Dalton, in the county of Livingston and State of New York, have invented certain new and useful Improvements in Land-Rollers; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

The main object of this invention is to have two rollers so arranged as to immediately follow each other or to swing over the first so as to run in line beyond the second one, overlapping a little to make a continuous leveling; also, in jointing the beam behind the first roller, so as to allow an up-and-down movement and a slight side play to the rollers, the continuation of the beam back of the joint making a journal for the second roller, and the invention as constructed will be understood by reference to the following specification and claims.

In the drawings, Figure 1 is a top plan, and Fig. 2 a side elevation, of the whole device.

A represents the first roller, and B the second. They are both made hollow or concave to near the center, and the journals rest in boxes or hubs formed in the center and not at the ends.

C is a metal beam or rod to which the pole a is attached in any suitable manner.

b is a journal which passes through the first roller, its outer end connected to a bent stay-piece, c, which is fastened at its other end to the beam C in front of the roller A. The inner end of the journal b is forked and provided with an eye, b', in each end, which receives the beam C. (See Fig. 1.) This allows an up-and-down movement or swinging entirely over of the roller A; but nuts or burrs d d are set on the beam each side the fork to keep the position of the journal on the beam, whether swung in front of roller B or at one side, as shown in Fig. 1, dotted lines indicating the roller when swung over.

Just back of roller A the beam C is jointed

at e by a coupling, as shown, or by any other suitable hinging device, and is then bent at nearly right angles a little way, then bent back in line with the front part, and then bent inward at right angles at f, so as to form the journal C' of the roller B, as shown in both figures. 55 Bending the beam at i allows the second roller in running to overlap the end of the first roller, and thus give a continuous leveling over a broader space. The joint e is also important, as it allows the rollers to turn easily and sharply 60 in corners and avoid bad places and also get a little lateral swing.

The body of the rollers is made of wooden staves bound around with iron hoops, hollow, except in the center, where the hub is placed, 65 giving therein the bearing for the axle suitably held in place. This part is made heavy and strong, and is either braced to the inside of the roller or is of a solid block fastened therein and the ends hollowed or concaved, 70 which makes the rollers heavier in the center, the axle running through the middle. If necessary, weights can be attached to the ends of the axles.

The seat D and foot-board g are attached to 75 the beam C, as shown.

A second brace, h, is attached to outside end of journal C', and the other end to the beam.

I claim—

1. The herein-described land-roller, comprising the rollers A and B, the roller A on a journal, C', whose inner end sets loosely on the beam C, and held in place by nuts or stops d d, arranged as described, and so as to swing over in front of the second roller, B, when desired, substantially as specified. 80

2. In a land-roller, the beam C, jointed at e, and bent at f, as described, forming the journal C', for the second roller, B, and in combination with rollers A, B, all substantially as and for 85 90 the purpose specified.

In witness whereof I have hereunto signed my name in the presence of two subscribing witnesses.

GEORGE C. FOOSE.
